UNITED STATES PATENT OFFICE

150,299

DESIGN FOR AN INSTRUMENT KEY GUARD
OR SIMILAR ARTICLE

Wallace G. Johnson, Baldwin Park, Calif.

Application November 2, 1946, Serial No. 134,469

Term of patent 14 years

(Cl. D56—1)

To all whom it may concern:

Be it known that I, Wallace G. Johnson, a citizen of the United States, residing in Baldwin Park, in the County of Los Angeles, State of California, have invented a new, original, and ornamental Design for an Instrument Key Guard or Similar Article, of which the following is a specification, reference being had to the accompanying drawing, forming a part thereof.

Figure 1 is a perspective view of an instrument key guard embodying my new and original design.

Figure 2 is a perspective view of the key guard shown in Figure 1 viewed from the opposite end.

Figure 3 is an end elevational view of the same on a reduced scale, the broken lines being for illustrative purposes only.

I claim:

The ornamental design for an instrument key guard or similar article, as shown and described.

WALLACE G. JOHNSON.
